UTILITY HOLDER FOR INFANTS' ACCESSORIES

Emma B. Price, Charlotte, N. C.

Application October 7, 1954, Serial No. 32,569

Term of patent 14 years

(Cl. D58—2)

I claim:

The ornamental design for a utility holder for infants' accessories, substantially as shown.
